UNITED STATES PATENT OFFICE.

JOSEPH H. BOURGON, OF DETROIT, MICHIGAN.

DESIGN FOR AN AUTOMOBILE-BODY.

52,125.

Specification for Design.

Patented July 2, 1918.

Application filed April 5, 1918. Serial No. 226,962. Term of patent 14 years.

To all whom it may concern:

Be it known that I, JOSEPH H. BOURGON, a subject of the King of Great Britain, residing at Detroit, in the county of Wayne and State of Michigan, have invented a new, original, and ornamental Design for Automobile-Bodies, of which the following is a specification, reference being had to the accompanying drawings, forming part hereof, in which the several parts are indicated by numerals, like parts being indicated by like numerals.

Figure 1 is an elevation of an automobile body taken as a side view.

Fig. 2 is a plan of a sectional detail taken approximately between the points $x-x$ along the line of the side of the body.

Fig. 3 is a perspective view of a section of one of the walls of a body.

1 and 1^a represent the two walls of the body of the automobile which are substantially parallel.

This design consists in so fashioning the top edge of each wall that it will have the section indicated in Fig. 3, with the wall face 1, the face 2 inclined outwardly and

the face 3 inclined inwardly with the approximately vertical face 4 and the inwardly inclined face 5, and the inner wall 6. The further feature of the design is that at either end of said walls respectively the faces 2 and 3 taper or converge toward a point as 2^a , such taper being at a point as 3^b , whereas at the forward end of the automobile the face 3 tapers from a point as at 3^a to a point as at α forming the apex of the cowl, whereas the face 2 tapers as at 2^b and is lost in the cowl.

It will be understood that the top of both of the walls 1 and 1^a are of identical construction.

What I claim is:

The design for an automobile body as shown and described.

Signed by me at Detroit, county of Wayne, and State of Michigan, this 2nd day of April, 1918.

JOSEPH H. BOURGON.

Witnesses:

WILLIAM MACGLASPAK,
M. CAUGHELL.
